CARPET STRETCHING APPARATUS

John H. Trew, McCandless Township, Allegheny County,
Pa. (8151 Edwood Road, Pittsburgh 37, Pa.)
Filed Oct. 8, 1962, Ser. No. 229,779
7 Claims. (Cl. 45—24)

This apparatus relates to apparatus for stretching a carpet to a desired length and maintaining it at that length to avoid shrinkage of the carpet. The invention is particularly advantageous in stretching wet carpet material to proper length after it has been cleaned and then maintaining the material stretched while the fibers dry.

This application is a continuation-in-part of my pending application Serial No. 111,717, filed May 22, 1961, now abandoned.

It has long been known that when carpet is cleaned, the wetting of the fibers tends to shrink them. This does not create a problem with the woof, or cross fibers, which are woven through the warp, or longitudinal fibers. The woof fibers are relatively loose when they are placed and they are generally of relatively small size, so that shrinkage of them does not affect the width of the carpet material, even if it has been woven on a broad loom to a large width. The warp fibers are woven under tension, however, and shrinkage in them has a very appreciable effect on the length of the material. It has been customary to employ various devices for the purpose of stretching the warp fibers of wet carpet while it dries for the purpose of keeping the length of carpet as desired. Conventional schemes have included the use of frames to which one end of the carpet is attached and which are then raised in the air. Weights are then hung from the other end of the carpet. In some cases the carpet is hung over a bar and weights are attached to each end. The prior art devices have all been subject to disadvantages. They require a careful determination of the amount of weight to be attached. Too small a weight permits a partial shrinkage and results in a carpet being shorter than desired. If too great a weight is attached, the carpet may be overstretched and be too long when it has dried. Many of the prior art schemes have placed noticeable creases in the carpet.

I have invented new and useful carpet stretching apparatus which avoid these shortcomings, which provide means for stretching a wet carpet to proper length as well as for maintaining the carpet stretched to the proper length while it is drying, which avoid deforming the carpet or putting any noticeable creases into it, which avoid shrinkage or overstretching of the dried carpet, and which leave the ends of the carpet intact and unmarred.

I provide a plurality of carpet stretching frames which are generally planar. I prefer to deform each frame by bending it along one side thereby offsetting one edge of the frame out of the plane of the frame. I preferably form the frame of a plurality of spaced apart bar-like members and bend them in a curve at their ends on one side of the frame, the frame thereby defining a generally planar structure which approximates a section of a cylinder at one edge of the plane. The frame is adapted to receive carpet which lies upon and follows the plano-cylindrical surface. I form the frame member at the bent portion thereof of adequate solid material to require carpet placed over the frame to follow the bent portion of the frame and restrain it from describing a tangent between the bent frame sections. I may attach a sheet-like member at the bent portion of the frame and shape it to follow the curve of that part of the frame, the sheet-like member becoming effectively a part of the frame. I may also provide a plurality of cross members in place of said sheet-like member. I hingedly connect the offset edges of the two frames for movement between a flattened position and

2

a folded position. I prefer to form the frame members of substantially tubular sections. I preferably provide hinge means having a plurality of extending portions adapted to fit within said tubular sections whereby the several frame members are joined to the hinge means. I further provide transversely extending portions from said hinge means whereby a plurality of frame members may be fitted together side by side where large pieces of carpet are to be stretched.

10 I further provide carpet gripping means for each frame. I preferably fix said gripping means adjustably to the bar-like members comprising the frame for movement toward and away from the offset edge of the frame. I prefer to provide carpet gripping means in which one tubular member is rotatably positioned within another tubular member. Preferably, I provide longitudinal slots in said tubular members which may be brought into registration or moved out of registration engaging the carpet between the edges of said slots. I further preferably provide locking means for locking said tubular members into desired relative position. I further preferably provide means to maintain the frame members in folded position at which time, because of the offset in the frame members, the distance between the carpet gripping members will be greater than when the frame members are flat.

Other details, objects, and advantages of my invention will become apparent as the following description of certain present preferred embodiments thereof proceed.

In the accompanying drawings, I have illustrated certain present preferred embodiments of my invention in which

FIGURE 1 is a side view of a carpet stretching apparatus embodying one form of my invention in flattened position and with a length of wet carpet in place;

35 FIGURE 2 is a side view of my carpet stretching apparatus in folded position;

FIGURE 3 is an end view of the carpet stretching apparatus in folded position;

FIGURE 5 is a sectional view taken along line V—V of FIGURE 2;

FIGURE 6 is a sectional view taken along line VI—VI of FIGURE 4;

45 FIGURE 7 is a partial sectional view of the carpet stretching apparatus at the hinged joint;

FIGURE 8 is a side view of another form of my invention generally corresponding to FIGURE 2;

FIGURE 9 is an end view of the apparatus shown in

50 FIGURE 8;

FIGURE 10 is an enlarged view of the hinge means of the apparatus shown in FIGURES 8 and 9;

FIGURE 11 is an isometric view of the hinge means shown in FIGURE 10;

55 FIGURE 12 is an enlarged elevational view of the clamp means shown in FIGURE 9; and

FIGURE 13 is an isometric view of the clamp means shown in FIGURE 12.

60 The carpet stretching apparatus shown in FIGURES 1 to 8 comprises two generally planar frame members 1 and 2. Each frame member has three L-shaped legs 3 which are preferably of ordinary angle stock. Each leg has a section 4 at the upper end which is bent over in a curve out of the plane of the frame member. Although the frames are generally planar, the curved ends 4 of legs 3 bend out of that plane in a generally cylindrical manner. The extremities of legs 3 which define one edge of the frame have holes drilled in them and are hingedly connected by a hinge member. A wing nut 20 and screw 21 through the holes in each of the opposed legs 3 may conveniently be employed as a hinge. A cross member

5 which is also L-shaped in cross section extends transversely across the frame near its upper end and is welded to each of the legs 3. A sheet-like member 6 is welded on the outer face of the legs 3 and follows the curved section 4 from cross member 5 around the curve 4 to the end of the legs 3. The edge of the sheet along the edge of the frame has a rolled section 7 which will not cut carpeting stretched over the frame and which provides rigidity for the sheet where it is unsupported between the ends of legs 3. Sheet 6 is preferably welded to legs 3 and cross member 5 and to the curved section 4 of legs 3. Member 6 is preferably imperforate, or it may be perforated so long as it is sufficiently solid to require carpet material placed over the frame to follow the curved section 4 of legs 3.

A carpet gripping member is adjustably positioned to legs 3 transversely of each frame. It comprises an L-shaped member 8 welded to clamps 9 which are positioned to each of the legs 3. Each clamp 9 comprises an L-shaped section 10 which fits around leg 3 and has lips 11 and 12 which encircle the edges of leg 3 and prevent the clamp from moving except by sliding along leg 3. A thumb screw 13 has threaded portion 14 which engages a matching thread in the clamp and bears against leg 3. When the thumb screw is tightened it locks the clamp securely to leg 3.

When the frames are laid flat the span between them is substantially less than the distance around the bent portions. This will be readily apparent from the geometry of the apparatus, the straight line of the carpet being shorter than the two curved lines of the frame between the same point. It will be apparent, therefore, that the length between the carpet gripping members on the two frames is less when the frames are laid flat (FIGURE 1) than when the frames are folded (FIGURE 3) due to the offset in the edges of the carpet gripping frames.

A number of holes 14 are drilled in member 8 and sharp pins or spikes 15 are inserted in its holes and welded therein.

Two bars 16 and 17 are hinged to frame 2 at 18 and have a notch at their other ends which drop over a pin at 19 thereby locking the carpet stretching frames in folded position as shown in FIGURES 2, 3, and 7.

In using the carpet stretching apparatus, the clamps 9 are loosened and the carpet gripping members are moved up and down on legs 3 until the distance from one carpet gripping member to the other around the top of the two frames when they are in folded position is slightly shorter than the length of the carpet. The frames are then laid flat as shown in FIGURE 1. The carpet, which will ordinarily be of shortened length because of shrinkage, is laid upon the frames and the ends are impaled upon pins 15. The frame is then folded which will stretch the carpet around the frames since the offset causes the length along the frame between the carpet gripping members to be increased when the frames are in folded position. In this manner, the carpet is stretched to a finished length while it is still wet. Bars 16 and 17 are dropped over the pins at 19 to lock the frames in position and the carpet is allowed to dry. It will, of course, be held at finished length throughout the drying process so that when the carpet is dried it will be precisely the desired length. The carpet material follows the gentle curve of the frames. When it is dry there are no sharp bends or creases to mar the appearance of the carpet material.

In the form of the invention shown in FIGURES 9 to 13 generally planar frame sections are provided. Each is formed of three legs 33 which are formed of tubular material and which have their ends bent into a generally cylindrical form. Stretchers 34 are clamped to the legs 33 adjacent their cylindrical sections. The cylindrical portions of legs 33 terminate and are connected together by hinges 39. Carpet clamps 38 are adjustably clamped to legs 33. Locking bars 36 are clamped to one of each pair of opposed legs by a clamp 35 and are notched or slotted

5 to engage a pin 37 fastened to the opposite leg 33. A section of a carpet is stretched upon the apparatus as indicated at 40 (FIGURE 9). The carpet stretcher is comprised of a plurality of pairs of legs 33 which, when folded 10 may be likened to a trestle bent, and which are joined in extended side by side relationship by stretchers 34, carpet clamps 38, and members 41 extending between hinges 39.

Stretchers 34 are comprised of tubular members 42 which are positioned on the outside of legs 33 adjacent 15 the curved portions thereof at each of legs 33, a clamping bolt 44 is threaded into a hole in tube 42. Bolt 44 extends through a hole in leg 33 from the opposite side of leg 33. A shoulder 45 formed on bolt 44 bears against a pad 43 which fits adjacent leg 33 and permits tube 42 to be drawn tightly up against leg 33. Either or both of legs 33 and tube 42 may be flattened to give a greater common bearing surface.

Each hinge 39 is comprised of two hinge bolts 44 and 45 which have shanks 46 and 47 respectively on their free ends. The other ends of the hinge bolts terminate in pads 51 and 52 respectively which have flattened surfaces adapted to be placed in juxtaposition and to permit hinge-like motion between hinge bolts 44 and 45. Extensions 48 and 50 extend from the axis of rotation of the hinge bolts. A hinge pin 49 formed integral with extension 48 extends through holes in the pads 51 and 52 and is threaded into extension 50, keeping the various hinge pieces assembled.

Each carpet chain 38 is comprised of a bracket 55 and 30 attached components. Each bracket 55 is slidably mounted upon a leg 33. A set screw 56 is threaded into threads in bracket 55 and bears against leg 33 fixing bracket 55 in position. A brace 57 extending from bracket 55 supports an extended outer tubular member 59 which 35 extends along the length of the carpet stretching apparatus between legs 33. An elongated slot is formed in member 59 along its length. A second tubular member 58 is placed inside a member 59. Member 58 likewise has a slot extending along its length. Rods 60 are threaded into member 58 and extend through slots 59a formed 40 radially in members 59. Each rod 60 is threaded to receive a wing nut 61. When each rod 60 is at one end of slot 59a, as shown in FIGURE 12, the longitudinal slots in members 58 and 59 are in alignment and will receive 45 the mat 53 and nap 54 of a carpet to be stretched. After the end of the carpet is inserted, each rod 60 is moved toward the other end of slot 59a, moving the longitudinal slots out of register and gripping the end of the carpet.

Additional sections such as 33a, 41a, and 42a may be 50 fitted to the existing frames to form a frame of greater width. The extensions of the hinge members receive the bars extending between the hinges, inserts may be employed with the stretcher bars and with the clamps. The legs 33 may be lengthened by using extensions and inserts 55 which increase their length.

The apparatus is employed in much the same manner as the apparatus shown in FIGURES 1 to 7. The apparatus is spread flat, the clamps positioned, and the carpet ends are placed and fastened in the clamps. The frame 60 assembly is then folded as shown in FIGURE 9 and the carpet is dried to the desired length.

While I have described and illustrated certain present preferred embodiments of my invention, it is to be understood that I do not limit myself thereto and that my invention may be otherwise variously practiced within the scope of the following claims.

I claim:

1. In a carpet stretcher for stretching carpet material and maintaining it stretched to a desired length while the material dries, a pair of generally planar frame members 70 adapted to have the carpet stretched thereover substantially in the plane of the frame members, each frame member having a generally rectangular outline and each having one edge generally offset from the plane of the frame members, hinge means hingedly connecting the off-

set extremities of the frame members, and carpet end gripping means affixed to each frame member and extending generally parallel to the offset edge of said frame member and substantially in the plane of the frame member whereby the distance between said carpet gripping means along said planar frame members is greater when said frame members are folded than when they are flattened.

2. In a carpet stretcher for stretching wet carpet material and maintaining it stretched to a desired length while the material dries, a pair of generally planar frame members, each having a generally rectangular shape but having one edge bent out of the plane of said frame member, hinge means hingedly connecting the offset edges of said frames, carpet and gripping means affixed to each frame member, extending generally parallel to the offset edges of the frame member substantially in the plane of the frame member and adjustable toward and away from the offset edge whereby the distance between said carpet gripping means along said planar frame members is greater when said frame members are folded than when they are flattened.

3. A carpet stretcher for stretching carpet material and maintaining it stretched to precise length while said material dries, comprising a pair of frame members formed by tubular members which may be added to construct frames of larger size for drying larger carpets, the tubular members of each frame member forming a generally planar structure which is generally cylindrical along one edge, hinge means joining the edges of the frame members along the side thereof which has been developed in generally cylindrical form, stretcher members extending axially along the cylindrical shape adjacent the frame members and forcing carpet material to follow the curve of the frame members, carpet gripping means extending along the frame members axially of the cylindrical portion of said frame members but at a distance therefrom, said carpet gripping means being adjustable along the frame member toward and away from the generally cylindrical section whereby the distance between said carpet gripping means along said planar frame members is greater when said frame members are folded than when they are flattened.

4. Carpet stretching apparatus as claimed in claim 3 in which the hinge means include extensions extending axially of the axis of rotation of the hinge whereby addi-

tional sections may be added to the frame members thereby increasing the size of the frame member.

5. Carpet stretching apparatus as claimed in claim 3 in which the carpet gripping apparatus comprises concentric arranged tubular members in which slots are formed axially of the tubular members, said tubular members being relatively rotatable to bring their respective slots into and out of registration for freeing and clamping a carpet end, and clamping means effective to clamp the tubular members in relative fixed position restrained against relative rotation.

10 6. A carpet stretcher for stretching carpet material and maintaining its stretched to a desired length while the material dries comprising a pair of generally planar frame members, each frame member being formed in a generally cylindrical shape along one side whereby the edge of the frame along that side of the frame is bent out of the plane of the frame, stretcher members adjacent the generally cylindrical position of the frame to require carpet stretched on the frame to follow the curve of the frame, carpet gripping means fixed to the frame generally parallel to the axis of the cylindrical portion and adjustable toward and away from said cylindrical portion, hinge means hingedly connecting the offset edges of the two frame members, and means to hold the frame members in a folded position whereby the distance between said carpet gripping means along said planar frame members is greater when said frame members are folded than when they are flattened and whereby carpet material placed on the frames when they are in a flattened position is stretched and maintained in stretched position until it dries.

15 7. A carpet stretcher as set forth in claim 6 in which the carpet clamp comprises a concentric tubular member having axial slots, said tubular members being relatively rotatable whereby the slots are movable in and out of register to release and clamp carpet ends inserted in said slots, said tubular members having clamping means in operative connection therewith whereby the tubular members may be fixed in carpet gripping position.
